UNITED STATES PATENT OFFICE.

RANSOM Y. BOVEE, OF MAYWOOD, ILLINOIS, ASSIGNOR OF ONE-HALF TO ORLANDO J. BUCK, OF CHICAGO, ILLINOIS.

EXPLOSION ENGINE.

1,424,872.

Specification of Letters Patent. Patented Aug. 8, 1922.

Application filed November 27, 1917. Serial No. 204,192.

To all whom it may concern:

Be it known that I, RANSOM Y. BOVEE, a citizen of the United States, residing at Maywood, in the county of Cook and State 5 of Illinois, have invented certain new and useful Improvements in Explosion Engines, of which the following is a specification.

This invention relates to improvements in engines and one of the objects of the same 10 is to provide an improved combination and arrangement of the parts. A further object is to provide improved means for scavenging the burnt gases after each explosion by eliminating the usual compression space within 15 the cylinder, and to provide improved means for passing an explosive mixture past the point of ignition, during the ignition period, thereby eliminating a pocket of foul gases around the spark plug which pocket is 20 formed by the burnt gases from a preceding explosion, and thus preventing dilution of the fresh gas mixture, insuring perfect combustion.

A further object is to provide improved 25 means for maintaining the pistons in true alinement with the cylinder, thereby obviating the objectionable side thrusts on the pistons due to the reversing of the crank.

A further object is to provide an improved 30 construction of engine whereby the ordinary valves for controlling the ports are dispensed with, and a still further object is to provide an improved piston pump lubrication to all of the working parts.

To the attainment of these ends and the accomplishment of other new and useful objects as will appear, the invention consists 35 in the features of novelty in substantially the construction, combination and arrangement 40 of the several parts hereinafter more fully described and claimed and shown in the accompanying drawings illustrating this invention and in which;

Figures 1 and 2 are vertical longitudinal 45 sectional views of an improved engine of this character, constructed in accordance with the principles of this invention.

Figure 3 is a view partly in elevation and partly in vertical section as taken on line 50 3-3, Figure 1.

Figure 4 is a vertical sectional view taken on line 4-4, Figure 2.

Figure 5 is a horizontal sectional view of 55 the cylinder taken on line 5-5, Figure 1 and with parts omitted.

Figure 6 is a horizontal sectional view of the cylinder taken on line 6-6, Figure 1 and with parts omitted.

Figure 7 is a top plan view of the parts shown in Figures 8 and 9. 60

Figure 8 is a vertical sectional view on line 8-8, Figure 7.

Figure 9 is a vertical sectional view on the line 9-9, Figure 7.

Figure 10 is a detail perspective view of 65 the crank casing.

Figure 11 is a left hand elevation of Figure 12 showing the lubricating pump operating mechanism with parts broken away. 70

Figure 12 is a vertical sectional view taken on line 12-12, Figure 11.

Figures 13, 14, 15 and 16 are diagrammatic views of the operation of the pistons showing the positions they will assume with respect to each other during the different steps of the operation and also showing the manner of opening and closing the ports. 75

Figure 17 is a detail view in elevation of the piston rod, packing box or bushing. 80

Referring more particularly to the drawings, the numeral 20 designates a suitable support upon which the parts are mounted and this support is provided with an opening 21 therethrough, through which a portion of a combined crank hanger and cylinder head, designated generally by the reference numeral 22 is adapted to project. 85

The hanger portion of the element 22 embodies depending spaced converging portions 23 connected at the bottom as at 24, and the portions 23 may be of any desired length, and formed integral therewith is the lower head 25 of the cylinder 26. The element is held in position in any suitable manner, preferably by means of flanges or shoulders 27 which extend over the support 20 and are secured thereto in any suitable manner. 90

The head 25 is hollow as at 28 and is 100 spaced a short distance from the support 20 to facilitate cooling the end of the cylinder in a manner to be set forth, and the head is provided with a laterally extending portion 29. 105

The cylinder 26 is supported by the head 25 and is provided with circumferential peripheral ribs or fins 30 and a head 31 at its other ends. The head 31 is also provided with a laterally projecting portion 32 110

arranged in alinement with the portion 29 of the head 25.

Reciprocating in the cylinder 26 is a hollow piston 33 having packing rings 34, and connected with this piston 33 is a hollow piston rod 35 which passes through a bushing 36 removably seated in the cylinder head 25.

This bushing 36 is preferably of a sectional construction embodying a cylindrical body portion 37 having external screw threads and a tapering extremity 38. The opposite end of the bushing member is reduced as at 39 to form a shoulder 40 and the portion 39 is provided with external screw threads.

The cylindrical portion 37 of the bushing is seated in a cylindrical opening in the cylinder head 25, to engage internal screw threads therein, and the tapering portion 38 projects into a conical opening 41 in the head. The sections of the bushings are held together by means of a suitable nut or collar engaging the threads on the portion 39 of the bushing, so as to clamp the sections together. The nut 42 is adjusted until it engages the shoulder 40 of the bushing, and a further adjustment of the nut in the same direction will tend to rotate the bushing members and force the tapering portion 38 into the conical seat 41 of the cylinder head 25, to form a tight joint between the piston rod 35 and the bushing. Suitable packing rings 44 are provided in a face of the bushing sections. However, the specific construction of this bushing forms the subject matter of a separate application, Serial No. 247,007, filed July 27, 1918.

Arranged to reciprocate in the hollow piston 33 is another piston 45 connected with 40 which is a hollow piston rod 46 which passes through one end of the hollow piston 33 and telescopes with the piston rod 35 thereof, and the piston 45 is provided with suitable packing rings 47 adjacent the inner face of the 45 wall of the piston 33.

In order to guide the pistons in true longitudinal relation to the cylinder so as to obviate or prevent the objectionable side thrusts on the pistons due to reversing of the 50 crank, there is provided a suitable guide 48 which is of a tubular construction, one end of which is removably secured in a threaded opening 49 in the connecting portions 24 at the base of the members 23 of 55 the crank hanger. This guide 48 is of suitable length and projects into the hollow piston rod 46 through the cylinder head 25 and preferably terminates at a point within the cylinder.

60 Arranged adjacent each end of the cylinder 26 and on one side thereof, are supplemental cylinders or valve chambers 50, 51. The laterally projecting portion 32 of the cylinder head 31 is adapted to form one end 65 of the chamber 50, and is provided with an

opening 52 to form communication between the chamber 50 and the atmosphere. The other end 53 of the chamber 50 is also open. This chamber 50 is provided with ports 54, 55 connecting with the interior of the cylinder 26 at one end thereof and with which a port 56 in the hollow piston 33 at one end is adapted to alternately communicate, the port 56 being provided with an elongated portion 57.

The hollow piston 33 is also provided with a port 58 at its other end, having an elongated passage 59 communicating therewith and is adapted to be alternately moved into and out of communication with an intake passage 60 which leads into the cylinder 26 and through which passage the fuel is supplied. The port 57 is also adapted to be moved into and out of communication with the intake 60.

Arranged within the valve chamber 50 are spaced reciprocating piston valves 61, 62, which are connected by means of a hollow piston rod 133, and the valves 61, 62 are so arranged as to control the ports 54, 55 in a manner which will be hereinafter set forth.

The opposite end of the cylinder 26 is provided with ports 64, 65, similar to the ports 54, 55 and these ports 64, 65 have communication with the valve chamber 51.

Reciprocating in this valve chamber are spaced piston valves 66, 67, and the piston rod 63 of the valves 61, 62 is connected with the piston valve 66 so that the valves will move in unison. A piston rod 68 is connected with the piston valve 67 and serves as a means whereby the valves may be reciprocated.

Leading from the chamber 69 which is formed by the laterally projecting portion 29 of the cylinder head 25 and the end of the valve chamber 51 is an exhaust passage 70.

Surrounding the cylinder and the valve chambers 50, 51 is a casing 71 having an open end 72, and inwardly spaced circumferential ribs or flanges 73 which are arranged in staggered relation with respect to the cooling ribs or flanges 30 on the exterior of the cylinder. These flanges or ribs 73 terminate short of the outer face of the cylinder 26 and the ribs or flanges 30 terminate short of the outer wall of the casing so that when cooling air is drawn into the casing 73, in a manner to be hereinafter set forth, the air will circulate in a tortuous passage lengthwise of the cylinder. Bearings 74, 75 are supported from the hanger 23 by means of suitable supports 76, secured to the flanges 77 of the element 23 by means of the fastening devices 78. These bearings 75, 76 are spaced from each other and preferably arranged in alinement. Journaled respectively in the bearings 74, 75 are portions 79, 80 of a hollow crank shaft and connected respectively to these portions are crank arms 81, 82 hav-

ing crank pins 83, 84 respectively secured thereto, and the crank pins are located opposite to but terminate short of each other and are connected by means of an intermediate 5 crank pin 85. Twin parallel crank rods 86, 87 are respectively pivotally connected by one extremity with the crank pins 83, 84 and the other extremities of these crank rods are pivotally connected to a wrist pin 88 and 10 to which wrist pin the lower extremity of the hollow piston rod 35 of the hollow piston 33 is detachably connected, such as by means of screw threads or the like, so that when the crank arms 81, 82 are rotated, a reciprocatory 15 movement will be imparted to the hollow piston 34 within the cylinder 26. A crank rod 89 is pivotally connected by one end to the crank pin 85, and this crank rod 89 may be constructed of separate members 20 or of a single member having one end connected and the other end bifurcated to form arms 90 which are pivotally connected by their free end to a wrist pin 91 and to which wrist pin 91 the free end of the hollow piston rod 46 of the piston 45 is detachably 25 connected, such as by means of screw threads or the like. It will thus be seen that when the crank is rotated the pistons 33, 45 will be reciprocated, a portion of the time the pistons 26 will be moving in opposition to each other, another portion of the time one of the pistons will be maintained relatively at rest while the other is reciprocating, and during another portion of the time, the pistons 35 will be moving in the same direction but at different rates of speed. The valves 61, 62, 66, 67 are adapted to be reciprocated 40 at the proper intervals of time in any suitable manner, but preferably by means of a cam 92 which is connected with the portion 80 of the crank, to rotate therewith, and this cam 92 is provided with a laterally projecting peripheral flange 93 adapted to travel between two rollers 94, 95 mounted 45 upon a sliding support 96, and which support is adapted to move upon suitable guides 97 so that when the cam is rotated, a reciprocatory movement will be imparted to the member 96 through the medium of the 50 rollers 94, 95. In order to take up the wear between the rollers and the cam, the roller 97 is preferably mounted upon a separate support 98 secured to the element 96, by means of suitable fastening devices 99, and 55 arranged between the supports 96, 98 are shims 100, and which shims may be readily removed or inserted between the parts when desired.

Connected with the member 96 and by one 60 end thereof is a hollow rod 101, the other extremity of the rod is connected in any suitable manner such as by means of a coupling 102 to the end of the hollow piston rod 68 of the piston valves, and if desired, a suitable bushing 103 may be provided for guid-

ing the piston valve rod 68. Stuffing boxes 104, 105 are respectively provided for the portions 79, 80 of the crank and these stuffing boxes may be held in position by means of suitable hanger members 106, 107 which 70 are secured to the supporting base 20.

A crank case 108 is provided for the crank and associated parts and this crank case is provided with slotted portions 109, 110 adapted to be closed by the hangers and members 106, 107 and to which members a portion of the crank case is detachably secured, so that when it is desired to remove the crank case 108, all that is necessary is 75 to remove the fastening devices 111 by means of which it is secured to the base 20, and the fastening devices 112 by means of which it is secured to the hanger members 106, 107, and the crank case may be lowered out of position. Thus it will be seen that 80 access may be readily had to the crank and parts thereof by simply removing the crank case without dismantling any of the other parts of the mechanism. Leading from the casing 71 which surrounds the cylinder 26 85 is a flue 113 which extends to a point adjacent the bottom of the crank case and on the outside thereof and is provided with a discharge opening 114 adjacent which discharge opening a fan 115 which is secured 90 to the portion 79 of the crank, rotates. When this fan rotates, it will be manifest that air will be drawn into the open end of the casing 71 to circulate in a tortuous passage along the outer face of the cylinder and 95 into the flue 113. At the same time air will be drawn in between the support 20 and the head 25 of the cylinder, into the hollow portion of the head, across the head and over the adjacent end of the cylinder to circulate 100 about the cylinder and into the flue 113, so that the engine cylinder will be efficiently and quickly cooled. The air which has been thus drawn into the flue 113 is discharged 105 therefrom by the fan 115 through the opening 114. The parts of the mechanism are lubricated from a sump 116, located preferably at the bottom of and exterior of the crank case, and with which sump, the crank case has communication through suitable 110 openings 117 in the wall of the crank case. A pipe 118 leads from the sump 116 and is connected at one end by means of a suitable coupling 119 with the hanger 23, preferably adjacent its bottom and to discharge into a 115 valve chamber 120 within which is located a valve 121. This chamber 120 has communication by means of a suitable passage 122 to a pipe 123 which is fixedly secured within the hollow guide 48 and the pipe 123 is of 120 such a length that it terminates adjacent the upper end of the guide. The pipe is also of an exterior diameter slightly less than the interior of the diameter of the guide so as to 125 form an oil passage between the pipe and 130

- guide, so that any excess oil discharged through the pipe will run down the outside thereof to be discharged from the guide 48 through a suitable opening 124 arranged adjacent its lower end. The oil is discharged through this pipe 123 by the operation of the piston 45, the movement of which in a direction away from the end of the pipe 123 will create a suction to draw out the oil, the valve 10 121 opening to permit the oil to enter the pipe 123. When the direction of movement of the piston 45 is reversed so that it will move towards the end of the pipe 123, the pressure upon the column of oil will close the valve 121 and the surplus oil from the pipe 123 will be discharged through the waste valve in the opening 124. The oil is drawn or sucked up through the pipe 123 on the up-stroke of the piston 45, and the oil which is not taken up through the ports communicating with the piston is discharged through the overflow port 124. During the reciprocation of the piston a portion of the oil which has been discharged through the passage 125 25 will enter the passage 126 in the piston 33 and be conducted thereby between the latter piston and the wall of the cylinder. Suitable openings are provided throughout the length of the telescoping elements 35, 46, 48 by means of which lubrication may be delivered between the parts, and by means of which also the bushing 37 may be lubricated. The wrist pin 88 is also provided with passages 127 adapted to receive the lubricant for oiling it, and the wrist pin 91 is also provided with passages 128 by means of which it may be lubricated, and these passages 127, 128 receive their supply of oil from the telescoping piston rods 35, 46.
- 40 The piston valves 61, 62, 66 and 67 are supplied with oil from the sump 116 by a pump mechanism, of which the sliding support for the rollers 94, 95 constitutes a part and to that end, there is connected with the sliding support 96, a tubular member 129 (see particularly Figures 4 and 12), which serves as a plunger operating in a chamber 130 and with which chamber a pipe 131 which leads from the sump 116 has communication as at 45 132, so that as the member 96 is reciprocated by the cam 82, the piston 129 will operate in the chamber 130 and will draw or suck the oil into the chamber from the sump, and the inlet to the chamber is controlled by a suitable valve. The oil is discharged from the chamber 130 into a pipe 133 which is arranged within the pipe 101 to extend therethrough, through the piston valves 67, 66, the piston rod 63, through the piston valve 62 and into the piston valve 61. This pipe 133 is open at its end and discharges into the piston valve 61 so that the oil will pass out of the passages 134 therein to lubricate the piston valve. The piston valves 62, 66 and 50 67 are provided with similar passages 134 for lubricating the valves.
- The pipe 133 is of a diameter somewhat smaller than the internal diameter of the piston rod 63 and pipe 101, so that some of the lubricant will pass down the outside of the pipe 133 and between said pipe and the pipe 101 to be discharged into a chamber 135 (see Figures 4 and 12) from where it will pass through suitable openings 136, 137 to lubricate the rollers 94, 95 and the extremity 75 of the passage 137 opens through one face of the member 96 to form an overflow for the oil.
- The chamber 130 is also provided with a suitable opening 138 by means of which the hollow portion 80 of the crank may be lubricated and openings 139, 140 are also provided, forming communication between the portions 80 and 84 of the crank shaft to lubricate these portions and also the central portion 85. Thus it will be seen that the parts will be automatically lubricated during the operation of the engine. Obviously suitable packing and packing rings may be provided at the points where they are needed. It will 90 also be manifest that the sliding member 96 serves as a double function of operating the piston valves 61, 62, 66 and 67, when reciprocated by the cam 82 and also as a means for operating or constituting a portion of the 95 plunger of the pump by means of which lubricating oil is raised from the supply and delivered to the various parts of the mechanism.
- This member 96 and the cylinder 130 being 100 supported independently of the crank case 108, it will be manifest that when the crank case is removed ready access may be had to these parts.
- The fuel is supplied through the intake 105 opening 60 to the cylinder 26 and will pass into the hollow piston 33 through the ports 57, 56, and 59, 58 to one side or the other of the piston 45 according to the position of the respective ports with respect to the intake 60, as will be understood, and during the simultaneous and relative reciprocation of the pistons 45, 33, the charge which has been taken into the piston 33 will be compressed between these pistons and at the 110 proper time, that is, when the ports 56, 57 and 58, 59 are in the proper position with respect to the ports 54, 55, the charge will be forced out of the piston 33 into the valve chamber 50 between the pistons 61, 62 115 and transferred into the cylinder 26 between the head or end thereof and the end of the hollow piston 33, at which time the explosion takes place. During this passage of the charge from between the pistons 45, 33, through the valve chamber 50 and into the cylinder between the end of the hollow piston and the cylinder head, the charge of 120 125

explosive mixture flows past the usual spark plug 141, during the ignition period, and is the point of ignition. This will eliminate a pocket of foul gases around the spark plug, and which pocket is usually formed by the burnt gases from a preceding explosion. This method of transferring the charge past the point of ignition will insure the maintenance of a rich mixture and the same will 10 not be thinned or diluted.

Just about the time that the explosion is to take place at the outer end of the cylinder 26, the ports 59, 58 of the outer piston 33 will be in a position to receive a charge from 15 the intake 60 which charge will be directed between the inner and outer pistons on the side thereof opposite to the side adjacent which the explosion is taking place and as the pistons move towards the inner end of 20 the cylinder, and the ports 59, 58 will be cut off from the intake 60. The charge thus received in the piston 33 will be compressed between the pistons and upon a further movement of the piston 33 in the same direction, the ports 59, 58 will be alternately moved into a position to communicate with the ports 64, 65 of the valve chamber 51 so 25 that the charge will be transferred from between the pistons, into the valve chamber 51 past the spark plug 141 and out of the port 30 65 into the cylinder 26 between the cylinder and the outer valve 33, the piston valves 66, 67 being shifted at the proper time to permit such a transfer of the charge. The charge 35 flowing past the ignition point during the ignition period will be exploded and the pistons will be driven towards the other end of the cylinder 26. During this movement of the pistons, the piston valves 61, 62 will be 40 moved so as to open the exhaust port 54 to permit the burnt gases to be scavenged from the opposite end of the cylinder and discharged through the opening 52 in the valve chamber. Likewise when the pistons 33, 45 45 have assumed a position that the explosion will take place at the opposite end of the cylinder, the piston valves 66, 67 will be in a position to open the port 65 so that the burnt gases at the opposite end of the piston 50 will be exhausted therefrom.

With this construction it will be seen that an improved engine will be produced and the burnt gases will be scavenged from each end of the cylinder after each explosion, 55 and furthermore the usual compression space within the cylinder is dispensed with as the compression of the charge is accomplished inside of the hollow piston and between the end of such piston and the piston 45, the gases being transferred after compression from the hollow piston through the valve chamber and into the cylinder between the end of the cylinder and the outer piston, the gases flowing past the spark plug while

under compression and during the ignition 60 period so that the explosion commences in the valve chamber.

The operation of this improved engine will now be described, particular reference being had to the diagrammatic Figures 13, 70 14, 15 and 16. As shown in Figure 13, the outer piston 33 is in the position which it will assume during an interval of rest just before the crank 84 reverses to move the piston in the opposite direction. At this period, the expulsion of the burnt gases between the end of the cylinder 26 and the piston 33 of a previous explosion has just occurred through the port 54 and out of the opening 52 of the valve chamber 50. The 80 piston valve 61 has just moved into the position shown, to close the port 54, after the discharge of the burnt gases, and the port 55 is in communication with the interior of the hollow piston 33, so that the compressed charge of fuel between the pistons 33—45 will be transferred through the ports 56, 57 and 55 into the valve chamber 50 between the piston valve 61—62. When the piston valve 61 is in a position to close the 90 port 54, the valve 61 will have moved substantially one half of its full stroke, and upon the completion of its full stroke in a direction towards the opening 52, the port 54 will be opened and the port 52 will be 95 closed, so as to permit the charge of fuel between the pistons 33—45, which has partially passed into the valve chamber 50 between the valves 61, 62, to be transferred 100 into the end of the cylinder 26 between the cylinder and the end of the piston 33, the piston 45 moving towards the end of the piston 33 to force the charge from between the pistons into the end of the cylinder, the valve 61 having assumed the position as shown in Figure 14. At the moment that the piston 45 assumes its nearest position to the end of the piston 33, as shown in Figure 14, the compressed charge of fuel between the pistons will have been completely expelled therough the ports 56, 55, 54 and into the end of the cylinder 26. As the piston 33 moves in the opposite direction and away from the end of the cylinder 26, communication between the ports 57, 56 and 55, will be cut off and the port 55 will be closed as shown in Figure 14, so that the products of combustion will be prevented from passing into the hollow piston 33, between the latter and the piston 45. At a 115 predetermined point in the movement of the pistons 33 and 45, downwardly or in a direction away from the end of the cylinder after an explosion has occurred, communication will be established between the port or passage 57—56, and the intake opening 60. During this latter movement the pistons 33—45 will be traveling in the same

direction, but the piston 45 will be moving at a greater rate of speed than the piston 33, due to the longer throw of its crank mechanism, so that when the passage 57 is in communication with the intake opening 60, a suction will be created through the ports 56—57, and a fresh charge of fuel will be drawn into the space between the pistons.

- 10 As the piston 45 travels towards the opposite end of the hollow piston 33, the ports 58, 59 and 64 will be brought into communication in the same manner as described with relation to the ports 55—56—57, and 15 the compressed charge of fuel between the lower end of the pistons 33—45 will be transferred into the valve chamber 51 past the spark plug 141, during the ignition period, and the valve 67 will be shifted to 20 open the port 65 to permit the charge to pass into the cylinder 26 and outside of the piston 33. The valve 67 is shifted at the proper time to permit of such passage of the charge, in the same manner as the valve 61, 25 and after the explosion, the valve 67 will be moved to the position shown in Figure 14 to permit the products of combustion to exhaust through the passage 65. On the upward movement of the piston 33, communication between the ports 64—59, 58 (see 30 Figure 16) will be cut off, and the port 64 will be closed, thereby preventing the products of combustion from passing back into the chamber between the pistons 33 and 45. 35 In Figure 13, the piston 33 has reached the limit of its travel through the explosion of fuel confined between its other end and the relatively opposed head of the cylinder 26. At this point the opening of the exhaust 40 port 65, permits the products of combustion to exhaust and the movement of the piston 33 towards the port 65, expels the remaining portion of the products upon the completion of the stroke of the piston, thereby 45 completely scavenging that end of the cylinder.

In Figure 14, piston 45 has reached the end of its stroke in the hollow piston 33 and the passages 58, 59 are in communication 50 with the intake passage 60. As the pistons 33, 45 simultaneously move downwardly or in the direction towards the opposite end of the cylinder 26, the passage 58, 59 will be moved out of communication with the intake passage 60, thereby confining a charge of fuel between the pistons 33, 45, to be compressed upon a continued movement of the pistons in the same direction, during 55 which latter period of movement, the piston 45 is traveling at a greater rate of speed than the piston 33, and at the time that the pistons 33, 45 assume the positions shown in Figure 15, the compressed charge is being transferred through the ports 58—59 and 60 64 past the sparking plug 141 and into

working position between the piston 33 and the end of the cylinder 26, through the port 65 when the latter is opened, at which time the ports will be in the positions shown in Figure 16.

Figure 16 shows the piston 45 at the nearest position it assumes to the other end of the piston 33, and in which position it has just expelled the compressed charge from between the pistons through the ports 70 64—65 into the end of the cylinder.

During this operation, the ports 57—56 will have established communication between the intake port 60 and the interior of the piston 33 on the opposite side of the 80 piston 45 admitting a fresh charge to be compressed on the opposite movement of the pistons, and as the piston 33 moves away from the end of the cylinder at which the last explosion has occurred, communication will at the proper point in its travel, be established between the intake and the ports 59—58 to permit a fresh charge to be drawn between the pistons 33—45 by the more rapid movement of the piston 45, 90 which causes it to move away from the end of the piston 33 creating a suction therebetween, which charge will be compressed when the pistons move in the opposite direction.

Thus it will be seen that an explosion will not only be obtained at each end of the cylinder on each stroke of the piston towards said end, but the cylinder will be completely scavenged of the products of combustion before a fresh charge of fuel is delivered into the cylinder, so that the charge will not be thinned or diluted by the mixture of burnt gases therewith. This is accomplished by reason of the fact that the outer piston travels substantially the entire length of the cylinder, the ends of the piston traveling in close proximity to the respective ends of the cylinder to force out the burned gases.

The actuating principle for deriving the 110 relative motions between the two moving pistons 33—45, is produced by the difference in throw of the connecting rods mounted in relative fixed relationship upon a common moving center about a crank shaft. The inner piston 45 is connected with its 115 crank by an arm or rod having a greater radius from the center of the crank motion than the piston 33, thus giving the piston 45 longer movement of travel in both directions than the piston 33, up and down or between the ends of the cylinder 26, and is fixed with relation to the crank at an angle of approximately thirty degrees with respect to a radial line passed through the 120 center of the axis of the connecting rod of the outer piston 33. This will produce what might be termed a following movement of the piston 45 with respect to the piston 33, and the piston 45 will alternately catch up 130

with the piston 33 at each end of the stroke and will relatively increase its speed beyond that end or head of the piston 33 from which it is moving, thereby creating an action equivalent to a double action pump within the said outer piston 33, and which latter piston through suitable ports permits the product of compression from between the piston 45 and the respective ends of the piston 33 to be alternately and at the proper moment, transferred through suitable ports, which latter at the proper time establish communication between the outer end of the piston 33 and the adjacent end of the cylinder 26.

The pump cylinder 130 being connected with the bearing of the hollow portion 80 of the hollow crank shaft, and the crank shaft being provided with a radial opening 138 therein, it will be manifest that as the crank shaft revolves in its bearing the opening 138 therein will be intermittently moved into and out of register or communication with the opening 130^a in the pump cylinder, so that during the operation of the pump a portion only of the oil which is drawn up thereby from the sump, will be discharged into the hollow crank shaft, which will occur only when the openings 130^a and 138 are in communication. When these passages are out of communication, the continued operation of the pump will cause the lubricating liquid to be forced through the tubular member 101. Obviously the opening 138 may be of any desired size according to the amount of oil it is desired to have delivered to the hollow crank shaft when the openings 130^a and 138 are in communication. After the oil is forced by the pump into this hollow portion 80 of the crank shaft, it will be manifest that it will flow into the communicating portion of the crank shaft to lubricate the respective bearings thereof.

45 The lubricating system has been herein specifically described to render a more complete and better understanding of the mechanism, but the construction and operation will not be specifically claimed in the present application.

What is claimed as new is:

1. An explosion engine embodying a cylinder having an intake and an exhaust port, a hollow piston reciprocable therein and closed with the exception of a port, a piston within the hollow piston and reciprocable axially with relation thereto, said port in the piston being movable into operative relation to the said intake of the cylinder for permitting the entrance of a charge of fuel into the hollow piston and between said pistons, and out of such relation, means for relatively reciprocating the pistons to compress the charge therebetween, and provisions for transferring said compressed charge from

between the pistons into the cylinder and between the end of the cylinder and hollow piston to be exploded, and an ignition chamber exterior to the cylinder, said charge during such transfer passing the ignition point in 70 said chamber during the ignition period.

2. An explosion engine embodying a cylinder having exhaust ports adjacent each end and an intake port, a hollow piston reciprocable in the cylinder, said piston having ports leading into the opposite ends thereof, a piston reciprocable in the hollow piston, means for reciprocating the pistons to alternately move the ports in the hollow piston into communication with the intake port to 80 receive a charge of fuel between the pistons and on opposite sides of the second recited piston, to be compressed between the pistons, and provisions by means of which the compressed charge will be transferred from between the pistons into the adjacent ends of the cylinder to be exploded, the said provisions embodying means for closing the outlet of the exhaust opening during the said transfer of the charge, whereby said outlet 90 will operate as a portion of the transfer passage, the said provisions embodying a chamber exterior to the cylinder, said chamber having two ports communicating with the end of the cylinder, and a chambered valve 95 co-operating with the said ports.

3. An explosion engine embodying a cylinder having exhaust ports in close proximity to each end and an intake port, a hollow piston reciprocable in the cylinder, and adapted to assume positions in close proximity to the ends of the cylinder to scavenge the end of the cylinder, said piston having ports leading into the opposite ends thereof, a piston reciprocable in the hollow piston, means for reciprocating the pistons to alternately move the ports in the hollow piston into communication with the intake port to receive a charge of fuel between the pistons and on opposite sides of the second recited piston, to be compressed between the pistons, provisions by means of which the compressed charge will be transferred from between the pistons into the adjacent end of the cylinder to be exploded, and an ignition device adjacent each end of the cylinder and past which device the respective charges will flow during the ignition period and while being transferred into the respective ends of the cylinder.

4. An explosion engine embodying a cylinder, a pair of reciprocating pistons one within the other and operating within the cylinder, means for supplying a charge of fuel between the pistons to be compressed therebetween, means for transferring the compressed charge from between the pistons into the cylinder between the end thereof and one of the pistons, and means for exploding said compressed charge during its 130

passage from between the pistons and into the cylinder, one of said pistons traveling the entire length of the cylinder into close proximity to the end of the cylinder to scavenge the said end of the cylinder.

5. An explosion engine embodying a cylinder, a pair of reciprocating pistons one within the other and operating within the cylinder, means for supplying a charge of fuel between the pistons to be compressed therebetween, means for transferring the compressed charge from between the pistons into the cylinder between the end thereof and one of the pistons, means for exploding the said compressed charge during the said transfer thereof, and means for closing the space between the pistons to the products of combustion of such explosion, the outer piston traveling the entire length of the cylinder and in close proximity to the end of the cylinder for entirely scavenging the cylinder.
- 10
- 15
- 20

25 6. An explosion engine embodying a cylinder, a pair of reciprocating pistons operating one within the other and within the cylinder, means for supplying a charge of fuel between the pistons to be compressed therebetween, means for transferring the compressed charge from between the pistons into the cylinder between the end thereof and one of the pistons, and an ignition device past which the said compressed charge flows when being transferred and during the ignition period, the outer piston traveling the entire length of the cylinder and into close proximity to the end of the cylinder for scavenging the cylinder.

30

35

40 7. An explosion engine embodying a cylinder, a pair of pistons operating one within the other and reciprocating within the cylinder, means for supplying a charge of fuel between the pistons to be compressed there-between, means for transferring the compressed charge from between the pistons into the cylinder between the end thereof and one of the pistons, and means for exploding said compressed charge during the said transfer thereof, the end of one of the pistons operating to close the space between the pistons to the entrance of the products of combustion, the other piston reciprocating the entire length of the cylinder and movable into close proximity to the end of the cylinder for scavenging the cylinder.

55 8. An explosion engine embodying a cylinder having an intake and an exhaust port, a hollow reciprocating piston within the cylinder closed with the exception of a port, a piston reciprocating in the hollow piston,
60 means for reciprocating the pistons to move the port in the hollow piston into communication with the intake to permit a charge to enter between the pistons, said port being also movable into communication with the
65 exhaust port, a valve chamber with which

the exhaust port communicates, said valve chamber also having an exhaust port, there being a second port forming communication between the valve chamber and the cylinder, and with which last recited port the port 70 in the hollow piston is adapted to communicate, whereby the charge between the pistons may be transferred through the valve chamber and into the end of the cylinder, a reciprocating valve for alternately opening 75 and closing the exhaust port, and an ignition device in the valve chamber and past which device the charge is passed while being transferred into the cylinder and during the ignition period. 80

9. An explosion engine embodying a cylinder having an intake and an exhaust port, a hollow reciprocating piston within the cylinder closed with the exception of a port, a piston reciprocable in the hollow piston, 85 means for reciprocating the pistons to move the port in the hollow piston into communication with the intake to permit a charge to enter between the pistons, said port being movable into communication with the exhaust port, a valve chamber with which the exhaust port communicates, said valve chamber also having an exhaust port, there being a second port forming communication between the valve chamber and the cylinder, 90 and with which last recited port the port in the hollow piston is adapted to communicate, whereby the charge between the pistons may be transferred through the valve chamber and into the end of the cylinder, a reciprocating valve for alternately opening and closing the exhaust port, and an ignition device in the valve chamber and past which device the charge is passed while being 95 transferred into the cylinder and during the 100 ignition period, said piston reciprocating means embodying mechanism for causing the pistons during a portion of their movements to travel in the same direction and at different rates of speed. 105

ing valve for alternately opening and closing the exhaust port, and an ignition device in the valve chamber and past which device the charge is passed while being transferred into 5 the cylinder and during the ignition period, said piston reciprocating means embodying mechanism for causing the pistons during a portion of their movements to travel in the said direction and at different rates of 10 speed, and during another portion of their travel to move in opposition to each other.

11. An explosion engine embodying a cylinder having an intake and an exhaust port, a hollow reciprocating piston within the 15 cylinder closed with the exception of a port, a piston reciprocable in the hollow piston, means for reciprocating the pistons to move the port in the hollow piston into communication with the intake to permit a charge to 20 enter between the pistons, said port being also movable into communication with the exhaust port, a valve chamber with which the exhaust port communicates, said valve chamber also having an exhaust port, there 25 being a second port forming communication between the valve chamber and the cylinder, and with which last recited port the port in the hollow piston is adapted to communicate, whereby the charge between the pistons 30 may be transferred through the valve chamber and into the end of the cylinder, a reciprocating valve for alternately opening and closing the exhaust port, and an ignition device in the valve chamber and past which 35 device the charge is passed while being transferred into the cylinder and during the ignition period, the end of the hollow piston operating to close the exhaust port to prevent the products of combustion from 40 passing into the hollow piston and between the pistons.

12. An explosion engine embodying a cylinder having an intake and an exhaust port, a valve chamber with which the exhaust port 45 communicates, said valve chamber also having an exhaust opening, there being a second port forming communication between the cylinder and valve chamber, a piston valve reciprocable in the valve chamber for controlling the exhaust port, an ignition device in the valve chamber, a hollow piston in the cylinder closed with the exception of a port, a piston reciprocable in the hollow piston, and means for reciprocating the pistons to 50 move the port in the hollow piston into communication with the intake to permit a charge to enter the piston and between the piston, said piston port being also movable into communication with one of the ports in 55 the valve chamber whereby the charge between the pistons may be transferred from between the pistons through the valve chamber and into the end of the cylinder exterior of the piston, said charge flowing past the 60 ignition device while being thus transferred, 65

and during the ignition period, and means for reciprocating the valve to control the exhaust port.

13. An explosion engine embodying a cylinder having an intake and an exhaust port, 70 a valve chamber with which the exhaust port communicates, said valve chamber also having an exhaust opening, there being a second port forming communication between the cylinder and valve chamber, a piston 75 valve reciprocable in the valve chamber for controlling the exhaust port, an ignition device in the valve chamber, a hollow piston in the cylinder closed with the exception of a port, a piston reciprocable in the hollow 80 piston, and means for reciprocating the pistons to move the port in the hollow piston into communication with the intake to permit a charge to enter the piston and between the pistons, said piston port being movable 85 into communication with one of the ports in the valve chamber whereby the charge between the pistons may be transferred from between the pistons through the valve chamber and into the end of the cylinder exterior 90 of the piston, said charge flowing past the ignition device while being thus transferred, and during the ignition period, and means for reciprocating the valve to control the exhaust port, the end of the hollow piston 95 operating to close the transfer passage to prevent the products of combustion from passing between the pistons.

14. An explosion engine embodying a cylinder having an exhaust port at each end 100 thereof and an intake, a hollow piston reciprocable in the cylinder and closed with the exception of a port leading to each end thereof, said piston reciprocating the entire 105 length of the cylinder and movable into close proximity to the respective ends of the cylinder for scavenging the cylinder, a piston reciprocable axially within the hollow piston, means for reciprocating the pistons to alternately move the ports in the hollow 110 piston into communication with the intake whereby a charge will be admitted into the hollow piston on the respective sides of the second recited piston, to be compressed between the pistons, provisions for transferring the compressed charge from between the pistons to the respective end of the cylinder to be exploded, and an ignition device disposed in the transfer passage at each end 115 of the cylinder and past which devices the 120 respective charges are transferred into the respective ends of the cylinder during the ignition period.

15. An explosion engine embodying a cylinder having an intake and an exhaust port, 125 a hollow piston reciprocable therein and closed with the exception of a port, said pistons reciprocating the entire length of the cylinder and movable into close proximity to the respective ends of the cylinder for

- scavenging the cylinder, a piston axially reciprocable in the first said piston, means for reciprocating the pistons to move the piston port into and out of communication with the intake whereby a charge will be received between the pistons and compressed therebetween, means for transferring the charge from between the pistons into the end of the cylinder, means for igniting the charge, telescoping hollow piston rods connected with the respective pistons, and a guide for maintaining the pistons and rods in true alignment with the cylinder, said guide telescoping with the piston rods.
16. An explosion engine embodying a cylinder having an intake and an exhaust port, a hollow piston reciprocable therein and closed with the exception of a port, a piston axially reciprocable in the first said piston, means for reciprocating the pistons to move the piston port into and out of communication with the intake whereby a charge will be received between the pistons and compressed therebetween, means for transferring the charge from between the pistons into the end of the cylinder, means for igniting the charge, telescoping hollow piston rods connected with the respective pistons, a hollow guide telescoping with the piston rods, and means for lubricating the pistons through the said guide and piston rods.
17. An explosion engine embodying a cylinder having an intake and an exhaust port, a hollow piston reciprocable therein and closed with the exception of a port, a piston axially reciprocable in the first said piston, means for reciprocating the pistons to move the piston port into and out of communication with the intake whereby a charge will be received between the pistons and compressed therebetween, means for transferring the charge from between the pistons into the end of the cylinder, means for igniting the charge, telescoping hollow piston rods connected with the respective pistons, a piston guide telescoping with the piston rods, an oil sump, and means whereby the oil will be raised from the sump by suction created by the piston for lubricating the pistons through the piston rods.
18. An explosion engine embodying a cylinder having an intake and an exhaust port, a hollow piston reciprocable therein and closed with the exception of a port, a piston reciprocable in the hollow piston, telescoping piston rods for the pistons, means for reciprocating the pistons to move the port into communication with the intake to permit a charge to enter between the pistons to be there compressed, means whereby the compressed charge will be transferred from between the pistons into the cylinder, means for exploding the charge, a sectional stuffing box through which the outer piston rod
- passes, and a guide for the pistons and rods, said guide telescoping with the pistons.
19. An explosion engine embodying a cylinder having an intake and an exhaust port, telescoping pistons, one of the pistons being hollow and the other piston reciprocating therein, telescoping piston rods for the pistons, means for delivering a charge of fuel between the pistons to be compressed, means for transferring the compressed charge from between the pistons into the cylinder, means for exploding said charge, an oil sump, means for conducting the oil from the sump by the suction of the piston to lubricate the pistons through the piston rods, a valve chamber, a reciprocating piston valve in the valve chamber, and means for conducting oil from the sump through the piston valve to lubricate the latter.
20. An explosion engine embodying an engine cylinder, pistons reciprocable in the cylinder, telescoping piston rods connected with the pistons, a crank shaft, connections between the crank shaft and the respective piston rods, said connections embodying wrist pins, and a guide for the pistons and rods, said guide passing through the wrist pins and telescoping with the piston rods.
21. An explosion engine embodying an engine cylinder, pistons reciprocable in the cylinder, telescoping piston rods connected with the pistons, a crank shaft, connections between the crank shaft and the respective piston rods, said connections embodying wrist pins, a guide for the pistons and rods, said guide passing through the wrist pins and telescoping with the piston rods, and means for lubricating the wrist pins through the said guide.
22. An explosion engine embodying an engine cylinder, pistons reciprocable in the cylinder, telescoping piston rods connected with the pistons, a crank shaft, connections between the crank shaft and the respective piston rods, said connections embodying wrist pins, a guide for the pistons and rods, said guide passing through the wrist pins and telescoping with the piston rods, an oil sump, and means for automatically conveying the oil from the sump to lubricate the pistons and the said wrist pins through the said guide.
23. An explosion engine embodying a cylinder, pistons reciprocable therein, hollow telescoping piston rods connected with the pistons, a crank shaft, a rod connection between the crank shaft and one of the piston rods and embodying a wrist pin, spaced parallel twin connecting rods between the crank shaft and the other piston rods, and embodying a wrist pin, the connection between the crank shaft and one of the piston rods having a greater throw than the connection between the crank shaft and the other piston rod, and a stationary guide

telescoping with the piston rods and passing through the wrist pins.

24. An explosion engine embodying a cylinder, pistons reciprocable therein, hollow telescoping piston rods connected with the pistons, a crank shaft, a rod connection between the crank shaft and one of the piston rods and embodying a wrist pin, spaced parallel twin connecting rods between the 10 crank shaft and the other piston rod and embodying a wrist pin, the connection between the crank shaft and one of the piston rods having a greater throw than the connection between the crank shaft and the 15 other piston rod, a stationary hollow guide telescoping with the piston rods and passing through the wrist pins, and means for automatically lubricating the wrist pins through the said guide.

25. An explosion engine embodying a cylinder, pistons reciprocable therein, hollow telescoping piston rods connected with the pistons, a crank shaft, a rod connection between the crank shaft and one of the piston 25 rods and embodying a wrist pin, spaced parallel twin connecting rods between the crank shaft and the other piston rod and embodying a wrist pin, the connection between the crank shaft and one of the piston rods 30 having a greater throw than the connection between the crank shaft and the other piston rod, a stationary hollow guide telescoping with the piston rods and passing through the wrist pins, and means for automatically lubricating the wrist pin through 35 the said guide by the suction created therein by the movement of the piston.

26. An explosion engine embodying a cylinder, pistons reciprocable therein, hollow telescoping piston rods connected with the pistons, a crank shaft, a rod connection between the crank shaft and one of the piston rods and embodying a wrist pin, spaced parallel twin connecting rods between the 45 crank shaft and the other piston rod and embodying a wrist pin, the connection between the crank shaft and one of the piston rods having a greater throw than the connection between the crank shaft and the 50 other piston rod, a stationary hollow guide telescoping with the piston rods and passing through the wrist pins, and means for automatically lubricating the wrist pins through the said guide, the said means embodying an oil sump, and a connection between the said hollow guide and the oil sump.

27. In an explosion engine having two pistons, one within the other, acting in the 60 same direction and at different speeds for a portion of their stroke, and then in opposite directions for the remainder of their stroke, means for introducing a charge into the outer piston and between the inner and outer pistons, means for transferring said

charge after compression from between the pistons and into the cylinder between the outer piston and cylinder head, and means for igniting said compressed charge on its passage from between the pistons and into 70 the cylinder and before it reaches the space between the outer piston and cylinder head.

28. In an explosion engine having two pistons, one within the other, acting in the same direction and at different speeds for a portion of their stroke, and then in opposite directions for the remainder of their stroke, means for introducing a charge into the outer piston and between the inner and outer pistons, means for transferring said 80 charge after compression from between the pistons and into the cylinder between the outer piston and cylinder head, and means for igniting said compressed charge on its passage from between the pistons and into 85 the cylinder and before it reaches the space between the outer piston and cylinder head, the last recited means embodying a passage exterior to the cylinder and adapted to form communication at a predetermined point 90 in the travel of the piston, between the space between the piston and the cylinder, and an ignition device disposed within the said passage and exterior to the cylinder.

29. In an explosion engine having two 95 pistons, one within the other, acting in the same direction and at different speeds for a portion of their stroke, and then in opposite directions for the remainder of their stroke, means for introducing a charge into the outer piston and between the inner and outer pistons, means for transferring said charge after compression from between the pistons and into the cylinder between the outer piston and cylinder head, and embodying an 100 exterior chamber, means for igniting said compressed charge on its passage from between the pistons and into the cylinder and before it reaches the space between the outer piston and cylinder head, the last recited means also embodying a passage 105 communicating with the space between the pistons and the said exterior chamber whereby the compressed charge will be ignited between the pistons before the charge is transferred 110 from between the pistons into the cylinder between the outer piston and cylinder head to be there expanded.

30. In an explosion engine having two 115 pistons, one within the other, acting in the same direction and at different speeds for a portion of their stroke, and then in opposite directions for the remainder of their stroke, means for introducing a charge into the outer piston and between the inner and outer pistons, means embodying a passage 120 exterior to the cylinder and adapted to be brought into communication with the space between the piston and also the space between the outer piston and cylinder head,

means for temporarily confining said charge within the said exterior passage, means for igniting said charge while confined within said exterior passage, and means for operating at a predetermined point in the travel of the pistons for releasing the confined charge into the engine cylinder between the outer piston and cylinder head.

31. In an explosion engine having two pistons, one within the other, acting in the same direction and at different speeds for a portion of their stroke, and then in opposite directions for the remainder of their stroke, means for introducing a charge into the outer piston and between the inner and outer pistons, means for removing the compressed charge from between the pistons, means for confining and igniting the charge thus confined, and means whereby the charge will be delivered into the space between the outer piston and cylinder head only after the charge has been ignited, and at a predetermined point in the travel of the outer piston.

32. In an explosion engine having two pistons, one within the other, acting in the same direction and at different speeds for a portion of their stroke, and then in opposite directions for the remainder of their stroke, means for introducing a charge into the outer piston and between the inner and outer pistons, means for transferring said charge after compression from between the pistons and into the cylinder between the outer piston and cylinder head, means for removing the compressed charge from between the pistons, means for confining the charge exterior of the cylinder, means for shifting the charge to deliver the charge into the cylinder between the outer piston and cylinder head at a predetermined point in the travel of the pistons, and means for igniting the charge.

33. In an explosion engine having two pistons, one within the other, acting in the same direction and at different speeds for a portion of their stroke, and then in opposite directions for the remainder of their stroke, means for introducing a charge into the outer piston and between the inner and outer pistons, means for transferring said charge after compression from between the pistons and into the cylinder between the outer piston and cylinder head, means for removing the compressed charge from between the pistons, and for confining the charge, the last recited means embodying a passage and spaced alined and connected pistons in the passage and between which pistons the charge is confined, means for moving the pistons to shift the charge to deliver the charge into the cylinder between the outer piston and cylinder head at a predetermined point in the travel of the pistons, and means for igniting the charge.

34. In an explosion engine having two pistons, one within the other, acting in the same direction and at different speeds for a portion of their stroke, and then in opposite directions for the remainder of their stroke, means for introducing a charge into the outer piston and between the inner and outer pistons, means for transferring said charge after compression from between the pistons and into the cylinder between the outer piston and cylinder head, means for removing the compressed charge from between the pistons, and for confining the charge, the last recited means embodying a chambered valve in the passage and in which chamber the charge is confined, means for reciprocating the valve, means for shifting the charge to deliver the charge into the cylinder between the outer piston and cylinder head at a predetermined point in the travel of the pistons, and means for igniting the charge.

35. In an explosion engine having two pistons, one within the other, acting in the same direction and at different speeds for a portion of their stroke, and then in opposite directions for the remainder of their stroke, means for introducing a charge into the outer piston and between the inner and outer pistons, means for transferring the charge from between the pistons into the cylinder between the head thereof and the outer piston, said means embodying a chamber exterior to the cylinder and having two ports in communication with the cylinder, a chambered valve movable in the said chamber and operable to establish communication between the two ports to transfer the charge within the cylinder, and also operable with relation to one of the ports to permit the products of combustion to pass out of the cylinder.

36. In an explosion engine having two pistons, one within the other, acting in the same direction and at different speeds for a portion of their stroke, and then in opposite directions for the remainder of their stroke, means for introducing a charge into the outer piston and between the inner and outer pistons, means for transferring the charge from between the piston, said means embodying a chamber exterior to the cylinder and having two ports in communication with the cylinder, a chambered valve movable in the said chamber and operable to establish communication between the two ports to transfer the charge within the cylinder, and also operable with relation to one of the ports to permit the products of combustion to pass out of the cylinder; the said valve also operating to close the last recited port to the atmosphere when the products of combustion have been expelled from the cylinder.

37. The combination of two pistons, one

within the other, a cylinder in which the pistons operate the outer piston having a port and a channel extending therefrom, said channel opening through the outer face 5 of the said outer piston and closed by the cylinder wall, compression rings carried by the piston on opposite sides of the said port and channel, there being a port in the cylinder wall adapted to be brought into communication with the said port and channel, said channel being sealed at its ends by the said rings when the channel is out of communication with the cylinder port, means embodying an outlet through the periphery 10 of the inner piston for lubricating the latter, spaced compression rings carried by the inner piston, on opposite sides of the last recited outlet, the last recited compression rings operating to confine the lubricant between the rings and to exclude admission of 15 gases into the oil area of the piston.

38. An explosion engine embodying two pistons one within the other acting in the same direction and at different speeds for

a portion of their stroke, and then in the 25 opposite direction for the remainder of their stroke, means for introducing a charge into the outer piston between the inner and outer pistons, means for transferring the charge from between the pistons into the cylinder 30 between the head thereof and the outer piston, the first and second recited means embodying a valve chamber, having a port, a piston valve reciprocable in said chamber for controlling the port, there being a lubricant opening through the periphery of the valve, means for supplying lubricant through said valve and out of said opening, and spaced compression rings carried by the periphery of the valve and on opposite 35 sides of the said opening for confining the lubricant between said rings, and excluding gases from the oil area of the periphery of the said valve.

In testimony whereof I have signed my 45 name to this specification, on this 21st day of November, A. D. 1917.

RANSOM Y. BOVEE.
